[57] CLAIM

The ornamental design for a light timer, as shown and described.

DESCRIPTION

FIG. 1 is a perspective view of the light timer embodying the design of the present invention.

FIG. 2 is a front elevational view thereof.

FIG. 3 is a top plan view thereof.

FIG. 4 is a side elevational view thereof, it being noted that the other side is identical to the side shown in FIG. 4.

FIG. 1

FIG. 2

FIG. 4

FIG. 3
